UNITED STATES PATENT OFFICE

RALPH A. WITTICK, OF LOS ANGELES, CALIFORNIA

GROOVE-CUTTING MACHINE

Application filed May 20, 1930. Serial No. 453,963.

My invention relates to groove-cutting machines and more particularly to a motor-driven machine for cutting grooves in concrete or terrazzo floors, pavements and the like.

The primary object of my invention is to provide a motor-driven machine which can be used to cut grooves rapidly and accurately in concrete floors and pavements so as to give them the appearance of having been constructed of blocks or flagstones.

A further object is to provide a groove-cutting machine for general use which has reversible parts whereby it may be adapted for right hand or left hand operation so that it may be made to work in opposite directions and on all parts of any open or restricted area.

Still another object is to provide a groove-cutting machine that can be adjusted to use a cutting wheel of any diameter, and to provide a machine that will cut grooves close to side walls and corners.

Other objects and advantages will appear hereinafter as the details of the invention are described.

Referring to the accompanying drawing which illustrates what is at present deemed to be a preferred embodiment of the invention.

Fig. 1 is a front-side view of my grooving machine.

Fig. 2 is a front-end view of the machine arranged for right hand operation as shown in Fig. 1.

Fig. 3 is a fragmentary sectional view, somewhat enlarged, showing details of construction, the section being taken approximately on line 3—3 of Fig. 1, through the front side only of the frame.

Fig. 4 is a sectional view, taken on line 4—4 of Fig. 3, showing details of the regulating lever.

Fig. 5 is a sectional view of the fan and fan casing which form a part of my invention, the section being taken on line 5—5 of Fig. 2.

Considered more in detail the drawing will be seen to show my grooving machine as comprising a low frame 10, preferably made

of angle-iron and having a pair of longer legs 11 equipped with relatively small adjustable castors 12, on its front side, and a pair of shorter legs 13 equipped with relatively large castors 14 on its rear side, said frame being adapted to carry a reversible electric motor 15 together with the necessary accessories whereby it may be controlled. These accessories include a conduit box 16 equipped with a power socket 17 adapted for connection with the plug 18 of an electric cord and a conduit box 19 having a suitable control switch 20 mounted thereon, said conduit boxes 16 and 19 being connected by a conduit 21 in which the necessary wiring is concealed. A lamp socket 22, into which a lamp cord may be plugged for night work, is also provided in conduit box 19.

In addition to adjustable castors 12, legs 11 are provided with a pair of grooved wheels 23 which are turnable on studs 24 projecting from the front side of the legs adjacent the lower ends thereof, said wheels being in exact alignment with each other so that they are adapted to run on a rail. The rail is preferably formed of relatively wide strips of heavy sheet metal 25, bent longitudinally so as to form a fold or bead 26 in the middle thereof which fits into the grooves of wheels 23, as is clearly shown in Figs. 2 and 3.

The rail 25 is provided with a wide bearing surface which rests upon the floor, and owing to said rail being provided along its mid-width with the upstanding fold or bend 26, said rail is particularly well adapted to cooperate with the grooved track wheels 23.

An arm 27 having a bearing 28 on its upper end through which a pivot bolt 29 extends axially into the front end of the motor shaft 30 and a bearing 31 on its lower end, in which a stub-shaft 32 turns, is attached by said pivot bolt 29 to the motor shaft which is extended sufficiently to provide space for fixing a double grooved pulley 33 thereon between said arm bearing 28 and the front bearing of the motor.

A double grooved pulley 34, of somewhat smaller diameter than said pulley 33, is fixed on the rear end of stub shaft 32 in alignment with said pulley 33, and a pair of thick belts

35, adapted to run in the grooves of said pulleys 33 and 34 are run thereover so that the latter pulley is driven by the former. Arm 27 is held in properly spaced relation to frame 10 by bolt 29 as it turns in bearing 28, and bolt 29 also serves as a pivot upon which arm 27 may be swung from one end to the other of the machine, as indicated in Fig. 1.

10 As an auxiliary means for maintaining arm 27 in a vertical plane at right angles to the motor shaft, a pair of parallel guide-bars 36 suitably spaced to permit said arm to work between the ends thereof, are provided, said 15 guide bars being supported in properly spaced relation to frame 10 by the two studs 37 fixed in a bar 38 which is fastened to the front side of legs 11 of the frame as shown in Fig. 3. Guide-bars 36 are bent in the 20 middle and are supported adjacent their middle points so that their free ends form two oppositely directed guide sections adapted to accommodate arm 27 in its movement through equal angles in either of its two positions.

An emery or a carborundum wheel 39, of suitable thickness to cut a groove of the desired width, is fixed on the front end of stub-shaft 32 in the usual way, the upper edge of 30 said wheel being covered by a guard 40 which is supported by a bracket 41, attached to arm 27, so as to protect the operator of the machine from flying particles and against accidental contact with the wheel. A fan 42 35 is attached to wheel 39 which has a suitable casing 43 supported on the rear side thereof in which the fan runs, said casing having an opening 44 in the under side thereof which directs the air current produced by the fan 40 toward the point at which the cutting action of the wheel is taking place.

A lever 45 adapted to hold arm 27 at a suitable working angle and thus to control the cutting depth of wheel 39, has a forked bearing 46 on its lower end which is adapted to turn on reduced portions 37' of studs 37. Said lever 45 is connected to arm 27 by a bar 47 having one of its ends attached to a pivot bolt 48 fixed in arm 27 somewhat below its 50 middle point. Oppositely disposed notches 49 adapted to engage a pin 50 which extends through lever 45 and projects from opposite sides thereof, are cut in the edges of connecting-bar 47 adjacent its free end. It will 55 be seen that this construction provides for changing the position of lever 45 from either of studs 37 to the other when the position of arm 27 is reversed and for adjusting connecting-bar 47 between them after such 60 changes have been made.

A bar 51 having holes 52 adjacent either end thereof is attached to the front end of motor 15 above its shaft and a helical spring 53, one end of which is attached to a hook 54 fixed in lever 45 has its other end hooked

into one of said holes 52, said spring being under sufficient tension to pull lever 45, when released, into a position which will hold wheel 39 out of engagement with the work. Obviously, when changes for reversed operation are made in arm 27 and lever 45, the position of spring 53 readily may be changed in accordance therewith.

An upright push-bar, 55, having its upper end 56 bent at right angles thereto to serve as a handle whereby the machine may be shoved along on its track, is inserted in a snugly fitting socket-piece 57 one of which is attached to each end of frame 10 adjacent the front side thereof. Said push-bar 55 is provided with an adjustable rack 58 which is held in close proximity to lever 45 in a plane parallel to that in which the lever moves and said lever is provided with a spring-controlled pawl 59 adapted to engage said rack 58, whether the latter is on one side or the other of the lever, as when in the position shown in Fig. 1 or when in the reversed position indicated by dotted lines. The purpose of rack 58 and pawl 59, it will be seen, is to hold lever 45, against the tension of spring 53, in a fixed position so that wheel 39 will cut in a groove of uniform depth after proper adjustment for that depth has been made.

Obviously when upright bar 55 is transferred to the other socket for reversed operation, as indicated in dotted lines in Fig. 1, the angular position of rack 58 must be changed. The rack being held by a clamping bolt 60 which is fixed therein and which extends through a fixture 61 on bar 55, this can be done by loosening nut 62 on bolt 60, turning the rack and bolt in fixture 61 to the proper new position and re-tightening nut 62.

Adjustable castors 12 are fixed in legs 11 so that they may be lifted clear of the surface upon which the machine is moving when wheels 23 are in engagement with rail 26 or may be forced downwardly upon said surface so as to raise the front side of the machine sufficiently to lift wheels 23 off of the rail. They thus serve to carry the front side of the machine when it is not in position for operation.

Such adjustability is secured by providing castors 12 with relatively long shanks 63 which extend through relatively short sleeves 64 attached to legs 11 so that the shanks are turnable and also movable vertically in the sleeves. The upper ends of said shanks have slightly rounded heads 65 formed thereon between which and said sleeves compressed helical springs 66 are mounted so as normally to hold the castors in their lifted position. Cams 67, in contact with said shank heads 65, are fixed adjacent the ends of a sleeve 68 which extends between legs 11 and is turnable on a bolt 69 passed therethrough and having its ends fixed in legs 11. Lever arms

70, adapted to turn sleeve 68, are secured thereto so as to be readily accessible at either end of the machine.

When the machine is not in position for 5 working, levers 70 are swung downwardly as indicated in Fig. 3 and cams 67 operate to force castors 12 down upon the floor surface so as to lift and carry the front side of the machine. The cams are so fixed in relation to 10 levers 70 that castors 12 are maintained in their lifting position, free from interference with the levers, until the latter are manually returned to their upper position as shown.

The machine is placed in position for operation 15 after the groove lines have been marked off on the surface upon which it is to be used. The rail is then laid parallel to the groove line upon which work is to begin and the machine is wheeled into position thereover 20 and its front side lowered as described above, so that its weight rests on the rail. The necessary electrical connections having been made, current is then turned on through switch 20, lever 45 is adjusted for the proper 25 cutting depth and the machine is shoved along on the rail by push-bar 55. As wheel 39 operates to cut the groove, fan 42, turning therewith, operates to blow out of its way dust and small particles which might interfere with its 30 action and thus reduce its efficiency and also to keep the groove line so clear of dust as always to be plainly visible.

The reversible feature of the machine makes it possible for the operator to extend the 35 grooves close to all corner portions of a room. It also adapts the machine for both right hand or left hand use in an efficient manner.

Claims:

1. A reversible groove-cutting machine 40 comprising a frame having a pair of longer legs equipped with adjustable castors on its front side and a pair of shorter legs equipped with non-adjustable castors on its rear side; grooved wheels adapted to run on a rail attached to said longer legs; a motor mounted on said frame so that its shaft extends horizontally in transverse relation thereto; an arm having one end pivotally attached to the shaft of said motor and the other extending 45 obliquely downward therefrom so that its free end may be swung about the axis thereof; a stub-shaft journaled in said arm, adjacent the free end thereof and in parallel relation to the shaft of said motor; aligned pulleys fixed 50 on the motor shaft and on one end of said stub-shaft; belting running over said pulleys; a grooving wheel fixed on the other end of said stub-shaft; guide bars attached to the front 55 side of said frame in spaced relation thereto, said guide bars being adapted to maintain said arm in a vertical plane at right angles to the shaft of said motor in either of its two positions; a reversible lever connected to said arm so that the angular position of the latter 60 may be changed or fixed thereby; and means to propell the machine with the track wheels thereof in engagement with said rail.
2. In a groove-cutting machine of the character described, a pivoted arm which may be swung from one end to the other of the machine, a cutting disc mounted in the free end of said arm to operate in either of its two positions; guide bars adapted to maintain 65 said arm in a vertical plane at right angles to the axis of its pivot in either of its two positions, and a reversible lever adapted to change or fix the angular position of said arm at either end of the machine.
3. A reversible groove-cutting machine comprising a frame having a pair of longer legs equipped with adjustable wheel supports on its front side and a pair of shorter legs on its rear side which are equipped with wheels, 70 a rail to guide the wheels which are carried by said pair of longer legs, a motor mounted on said frame so that its shaft extends horizontally in transverse relation thereto; an arm having one end pivotally attached to the shaft of said motor and the other extending obliquely downward therefrom so that its free end may be swung about the axis thereof; a stub-shaft journaled in said arm, adjacent the free end thereof and in parallel relation to the shaft of said motor; aligned pulleys fixed on the motor shaft and on one end of said stub-shaft; belting running over said pulleys; a 75 grooving wheel fixed on the other end of said stub-shaft; guide bars attached to the front side of said frame in spaced relation thereto, said guide bars being adapted to maintain said arm in a vertical plane at right angles to the shaft of said motor in either of its two positions; a reversible lever connected to said arm so that the angular position of the latter 80 may be changed or fixed thereby; and means to propell the machine with the track wheels thereof in engagement with said rail.
4. In a groove cutting machine of the character described, a pivoted arm swingable from one end to the other of the machine, a cutting disc mounted in the free end of said arm to operate in either of two positions, means to maintain said arm in a substantially vertical plane at right angles to the axis of its pivot in either of its two positions, a connecting bar pivotally attached to said arm at a distance from the pivot thereof, and a reversible lever having a detachable connection with said connecting bar thereby adapting said lever to fix the angular operative position of said arm when the latter is directed toward either end of the machine.
5. In a groove cutting machine of the character described, a pivoted arm swingable from one end to the other of the machine, a cutting disc mounted in the free end of said arm to operate in either of two po- 125

sitions, means to maintain said arm in a substantially vertical plane at right angles to the axis of its pivot in either of its two positions, a connecting bar pivotally attached to said arm at a distance from the pivot thereof, and a reversible lever having a detachable connection with said connecting bar thereby adapting said lever to fix the angular operative position of said arm when the latter is directed toward either end of the machine, said connecting bar having notches cut into opposite edges thereof to afford a detachable operating connection of said reversible lever therewith in either of the reverse positions thereof.

In testimony whereof I hereunto affix my signature.
